HAIRDRESSING TOOL

Herman C. Schlicker, Brooklyn, N. Y., assignor to
 Elococurl Corporation, New York, N. Y., a corporation of New York

Application November 25, 1939, Serial No. 306,040

19 Claims. (Cl. 132—35)

The present invention relates to hair-dressing tools, and is more particularly directed toward hair-dressing tools having a mandrel slotted to receive a disappearing comb so that hair may be wound about the mandrel to form a curl.

In hair-dressing tools of the type referred to the disappearing comb is adapted to be in an exposed position for combing the ends of the lock of hair and assisting in starting the winding of the curl, or to be housed in the mandrel so that the wound coil of hair may be readily removed from the mandrel.

The present invention contemplates the positioning of the disappearing comb within a slot of depth greater than the radius of the mandrel, and off center of the mandrel axis, thereby permitting the disposition of one of the shanks of a bob pin within an axially aligned opening extending inwardly of the end of the mandrel.

Another object of the invention is to arrange the hair curling device so that when the hair securing member (preferably in the form of a disappearing comb insert) is in position to hold the hair during the winding operation, the bob pin is held on the mandrel against accidental removal and out of the winding zone defined by said hair securing member and so that only after completion of the winding operation and release of the hair is it possible to pass the bob pin along the mandrel to bring the exposed shank opposite the winding zone.

The present invention further contemplates the application of a bob pin, one of the shanks of which is undulated in association with the mandrel of the hair-dressing tool, and provides for the support and engagement of such bob pin, an annular projection at the end of the mandrel in conjunction with the axial opening extending inwardly of the mandrel, such annular projection having undulations complementary to those on the undulated shank of the bob pin, so as to permit the maintenance of the bob pin axially of the mandrel while at the same time it is distant from the tress winding zone of the mandrel, the rotation of the bob pin axially of the mandrel so that the bob pin may be in a position in line with the end of the curled tress and adjacent the scalp, and the spreading of the bob pin under tension as the same is urged inwardly and longitudinally along the mandrel at the desired position close to the end of the curl adjacent the scalp. The annulated formation of the mandrel is applicable to hair-dressing tools having hair holding means of the clamp type as well as to those with the disappearing comb type.

In order to reduce the weight of the device and its cost, as well as to facilitate molding operations, the mandrel is provided with a recess communicating with the hairpin receiving opening and extending outwardly through the side of the mandrel. This recess has an end wall to form a stop for the inserted shank of the hairpin.

10 The present invention also contemplates improved mechanism for controlling the movements of disappearing comb inserts. The devices employed include a small leaf spring and follower both carried in an opening extending transversely of the disappearing comb insert and adapted to cooperate with a cross member carried by the sheath.

15 Other and further objects will appear as the description proceeds.

The accompanying drawings show, for purposes of illustrating the present invention, two of the many embodiments in which the invention may take form, it being understood that the drawings are illustrative of the invention rather than limiting the same.

In these drawings:

20 Figures 1 and 2 are side elevational and top plan views of a hair-dressing tool with the disappearing comb insert exposed and the bob pin in initial position;

25 Figure 3 is an elevational view of the tool with the insert sheathed and the bob pin completely inserted;

30 Figure 4 is an end elevational view;

35 Figures 5, 6 and 7 are sectional views on the lines 5—5, 6—6 and 7—7, respectively, of Figure 1;

40 Figures 8 and 9 are fragmentary views similar to Figures 1 and 3 showing a modified form of construction; and

45 Figure 10 is a section on the line 10—10 of Figure 8.

The body member 10 of the hair-dressing tool is usually made in the form of a molded plastic article. It has a series of combing teeth 11 at one end and a mandrel 12 at the other end. This mandrel is generally cylindrical shape, but may, as shown in the drawings, taper slightly to stiffen the article and to facilitate removal of the hair wound around the mandrel.

50 The mandrel end of the tool is provided with a longitudinally extending slot 13 with widened portion 13a near the outer end of the slot and adapted to receive a toothed insert or disappearing comb 14 with a laterally extending element 14a. This insert has two thumb pieces 55 15, 15, the upper one extending out through the

slot 13 and the lower one extending out through a lower opening 16. They are for use in manipulating the insert. This end of the insert is provided with tongues 17 adapted to fit into grooves 18 in the body member to provide guides to insure that the insert can reciprocate laterally and cannot move in any other direction. A pin or cross member 20 extends through the sheath walls and through an opening or aperture 21 in the insert. This pin acts to keep the insert in place and to limit the extent of its movement. The insert is held in either extreme position by a follower 22, which may be notched or cut back at the ends, as indicated at 23, and pressed against the pin 20 by a small spring 24. The spring and follower are received in the aperture 21 and are readily held in place when the device is completely assembled.

The mandrel end of the body member is provided with an axially extending hole 25 adapted to rotatably receive the shank 26 of a bob pin 27. When the insert is exposed in the hair retaining position, as in Figures 1 and 2, the bob pin cannot be completely inserted because it is stopped by the laterally extending element 14a formed on the insert opposite the opening 25 and in the path of the straight shank of the bob pin. The formation 28 at the mandrel end of the body member is undulated to provide annular ridge and valley formations 28' and 28'', respectively. Such ridge and valley formations are substantially complementary to the ridge and valley formations 29' and 29'' of the undulated shank 29 of the bob pin 27, so that normally during the winding operation of the tool the bob pin 27 may be maintained under tension axially of the mandrel and prevented from entering the zone on the mandrel where the hair tress is being wound. After the hair is wound the insert is depressed to enter the sheath, as shown in Figure 3 and in the dotted lines of Figure 5, thereby moving the extension 14a below the opening 25 so that when pressure is applied to the bob pin, the same is urged inwardly with its straight shank 26 being slid longitudinally within opening 25, and the undulated shank 29 being slid and under tension across the ridge and valley elements of the end formation 28 of the mandrel, the free portion of the undulated shank during such movement being spread sufficiently to pass over and be disposed adjacent the wound tress or curl on the mandrel.

In addition, by virtue of the annular ridge and valley formations 28' and 28'' of projection 28, the bob pin 27 may be rotated about its smooth shank 26 so that its undulated shank 29, having the ridge and valley formations, complementary to those of the end formation 28, may be disposed at any position radially of the end formation and the mandrel, thereby permitting the subsequent clamping or grasping of the wound curl by the bob pin at a position close to the end of the curl and adjacent the scalp, as the bob pin is slid inwardly upon completion of the curl preparatory to release of the curl from the mandrel.

As shown in the drawings, the disappearing comb receiving slot is deeper than the radius of the mandrel and is placed to one side of the mandrel axis, so that the slot 25 for accommodating the smooth shank 27 of the bob pin may be formed in the axis of the mandrel. By this arrangement the bob pin will be mounted for 360° rotation about the mandrel axis, thus permitting application of the bob pin for clamping

the end of the tress curl wherever it may be formed on the periphery of the mandrel. By virtue of this property the tress will be gripped by the bob pin as it is slid inwardly along the axis at the end of the curl formed on the mandrel. While the material required to form the right-hand or front wall of the sheath is, as shown in Figure 6, thicker, yet it is possible to materially reduce the weight of the device and facilitate molding operations by providing recesses such as indicated at 30 to 34. The recess 30 extends beyond the mandrel axis and communicates with the bob pin receiving slot 25. The web 35 between recesses 30 and 31 forms a stop for the end of the bob pin.

The body member is made of suitable plastic in a longitudinally split mold with a suitable blade for forming the comb receiving slot and pin for forming the bob pin receiving hole. The recesses 30 and 31 extend inwardly as far as possible and are formed by core like elements provided on the inside of the half of the die employed for the front face of the molded article. This makes it possible to employ a short pin in the mold to produce the opening 25.

The annulated end, the side recess and axial hole arrangement may be employed in rod and clamp type curlers as well as in curlers of the disappearing comb type. The provision of a stop element such as the lug 14a on the insert to control insertion of the bob pin is not confined to hair-dressing tools of the type where the comb insert has no longitudinal movement, but can in its broader aspects generally be applied to other types of hair-dressing tools. It may also be employed in hair-dressing tools without the annulated end.

In the arrangement shown in Figures 8, 9 and 10 the toothed insert 40 has an extension 41 movable in a slot 42 and adapted to depress a spring 43 carried in a recess 44. The end 45 of the spring has a hole 46 normally above the opening 25 in the mandrel, but adapted to be brought in line with it when the insert is in the inner position as shown in Figure 9. When the insert is exposed, as shown in Figure 8, the solid part of the spring 43 is opposite the opening 25 in the mandrel so that the bob pin shank is stopped.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. In a hair-dressing tool, a hair receiving mandrel having a peripherally annulated and longitudinally undulated end formation and an axial inwardly extending opening.
2. In a hair-dressing tool, a hair receiving mandrel, means on said mandrel for gripping strands of hair to be curled, a peripherally annulated and longitudinally undulated formation at the mandrel end, and an axial opening extending inwardly of the mandrel end.
3. In a hair-dressing tool, a substantially cylindrical body having a laterally opening comb receiving slot extending longitudinally thereof and disposed to one side of the body axis and an axially disposed hairpin shank receiving opening extending inwardly from the end of the body.
4. In a hair-dressing tool, a substantially cylindrical body having a laterally opening comb receiving slot extending longitudinally thereof

and disposed to one side of the body axis and an axially disposed hairpin shank receiving opening extending inwardly from the end of the body, and a peripherally annulated and longitudinally undulated hairpin shank spreading member formed at the end of the body and a transversely extending passageway between the comb receiving slot and the recess.

5. In a hair-dressing tool, a substantially cylindrical body having a laterally opening comb receiving slot extending longitudinally thereof and disposed to one side of the body axis and an axially disposed hairpin shank receiving opening extending inwardly from the end of the body, and a peripherally annulated and longitudinally undulated hairpin shank supporting and spreading member at the end of the body.

6. In a hair-dressing tool, a substantially cylindrical body having a laterally opening comb receiving slot extending longitudinally thereof and disposed to one side of the body axis and an axially disposed hairpin receiving opening extending inwardly from the end of the body, the body having a recess disposed laterally of the comb receiving slot and communicating with the pin receiving opening.

7. In a hair-dressing tool, a substantially cylindrical body having a laterally opening comb receiving slot extending longitudinally thereof and disposed to one side of the body axis and an axially disposed opening extending inwardly from the end of the body for receiving a shank of a hairpin, the body having a recess disposed laterally of the comb receiving slot and communicating with the pin receiving opening, and a transversely extending passageway between the comb receiving slot and the recess the end of said recess forming a stop to limit the extent of insertion of the hairpin shank.

8. A hair-dressing tool comprising a mandrel about which hair may be wound to form a curl, the mandrel having an axially disposed opening in the end to receive a hairpin shank, and an end formation such as to spread a hairpin, said end formation being peripherally annulated and longitudinally undulated to support and guide a hairpin for rotation about a shank in the axial opening of the body.

9. A hair-dressing tool comprising a mandrel about which hair may be wound to form a curl, the mandrel having an axially disposed hole in the end to receive a hairpin shank, and a peripherally annulated and longitudinally undulated end formation such as to spread hairpin shanks, the mandrel being further provided with a longitudinally extending laterally opening comb receiving slot to one side of the axial hole, and a toothed insert in the slot.

10. A hair-dressing tool having a mandrel, a hair-holding means carried thereby and movable between hair-retaining and hair-releasing positions, the mandrel having a bob pin retaining tip beyond the hair-holding means, and stop means effective when the hair-holding means associated with said hair holding means and is in the hair-retaining position to limit the insertion of the hairpin shank and ineffective to limit the insertion when in the hair-releasing position.

11. A hair-dressing tool comprising a mandrel about which hair may be wound to form a curl, a hair-holding means movable between releasing and retaining positions and carried by the mandrel to define a winding zone in which the curl may be wound, the mandrel end extending be-

yond the hair-holding means in the form of a tip portion, the tip portion having an axially extending opening adapted to receive the straight shank of a hairpin and an end formation to receive the serrated shank of the hairpin and hold it against accidental removal, and stop means associated with said hair holding means and effective when the hair-holding means is in the hair-retaining position to limit the insertion of the hairpin shank and ineffective to limit the insertion when in the hair-releasing position.

12. A hair-dressing tool comprising a mandrel about which hair may be wound to form a curl, the mandrel having a longitudinally extending opening to receive one shank of a hairpin and an end formation such as to spread the shanks, the mandrel also having a laterally opening comb receiving slot, a disappearing comb insert in said slot and movable between exposed and concealed positions, and means carried by the insert and effective to limit the insertion of the shank into the opening when the insert is exposed and ineffective when the insert is concealed.

13. A hair-dressing tool such as claimed in claim 12, wherein the said means is in the form of a laterally extending element carried by the insert and opposite the opening when the insert is in the exposed position.

14. A hair-dressing tool such as claimed in claim 12, wherein the said means includes a spring normally opposite the opening when the insert is in the exposed position.

15. A hair-dressing tool, comprising a mandrel about which hair may be wound to form a curl, a peripherally annulated and longitudinally undulated formation at the end of said mandrel, an axially disposed opening extending inwardly from the end of said mandrel, and a bob pin, one of the shanks of which extends within the axial opening, and the other of which has a surface configuration complementary to and rests against the periphery of the annulated formation on said mandrel, whereby said hairpin may be normally maintained for rotation about the axis of said mandrel, and for movement inwardly along said mandrel.

16. In a hair-dressing tool, a hair receiving mandrel having a peripherally annulated and longitudinally undulated end formation and an axial inwardly extending opening, and a bob pin associated with said mandrel and having a straight and an undulated shank, the straight shank of said bob pin being insertible into said opening, and the undulated shank upon insertion of the straight shank being maintained under tension at the periphery of the annulated end of said mandrel, whereby upon rotation of said straight shank in said opening, the undulated shank is displaced peripherally along the annulated end formation of said mandrel.

17. In a hair-dressing tool, a substantially cylindrical hair winding mandrel, the end of which is undulated to provide at least one annular formation, an axial opening extending inwardly of the mandrel end, and a bob pin associated with said mandrel and having straight and undulated shanks, said bob pin being mounted on said mandrel with its straight shank inserted in the axial opening, and its undulated shank resting under tension against the undulated annular formation of said mandrel, whereby said bob pin may be axially rotated with respect to the mandrel and at the end thereof, and displaced longitudinally of said mandrel for spreading the same to accommodate hair wound on said mandrel.

18. In a hair-dressing tool, a substantially cylindrical body having a laterally opening comb receiving slot extending longitudinally thereof and disposed to one side of the body axis, and an axially disposed hairpin receiving opening extending inwardly from the end of the body, an annular head formed at the end of the body, the same providing substantially longitudinally thereof continuous adjacent ridge and valley formations.

19. In a hair-dressing tool, a substantially cylindrical body having a laterally opening comb receiving slot extending longitudinally thereof and disposed to one side of the body axis, a comb reciprocable within said slot, an annular head at the end of the cylindrical body, an axially dis-

posed hairpin receiving opening extending inwardly through the head and the end of the body, a hairpin at least one of the shanks of which has a ridge and valley formation, the outer contour 5 of said head being of substantially ridge and valley formation, said hairpin being adapted to be maintained so that the other shank thereof extends within the hairpin receiving opening, and the first shank rests on said head with its 10 ridge and valley formations cooperating with the ridge and valley formations of the head, whereby said hairpin may be rotated about the axis of the body to a desired radial position with respect thereto and slide longitudinally of said body at 15 such radial position.

HERMAN C. SCHLICKER.
